Edgar Vale & Co.

UNITED STATES PATENT OFFICE.

EDWARD J. GEBHARDT, OF HOBOKEN, NEW JERSEY.

SLED.

1,391,312.

Specification of Letters Patent. Patented Sept. 20, 1921.

Application filed August 25, 1920. Serial No. 405,907.

To all whom it may concern:

Be it known that I, EDWARD J. GEBHARDT, a citizen of the United States, and residing at Hoboken, in the county of Hudson and 5 State of New Jersey, have invented certain new and useful Improvements in Sleds, of which the following is a specification, such as will enable those skilled in the art to which it appertains to make and use the 10 same.

This invention relates to sleds or what I call push sleds or sleds adapted, when in use, to be pushed over a snow covered surface but which are adapted to be drawn over said 15 surface or used in the manner of an ordinary sled in coasting, if desired; and the object of the invention is to provide a sled of the class specified with stationary runners and with adjustable or steering runner; a 20 further object being to provide an adjustable handle member by means of which the sled may be pulled over a surface and which also serves to operate the adjustable steering runners; and a still further object being 25 to provide a sled of the class specified with feet receiving recesses or apertures into which the feet of the operator may be placed and which are designed to prevent the slipping of the feet on the sled, or the body portion thereof; and with these and other objects in view the invention consists in a device of the class and for the purpose specified which is simple in construction and 30 operation and efficient in use, and which is 35 constructed as hereinafter described and claimed.

The invention is fully disclosed in the following specification, of which the accompanying drawing forms a part, in which the 40 separate parts of my improvement are designated by suitable reference characters in each of the views, and in which:—

Figure 1 is a plan view of my improved sled;

Fig. 2 a side view thereof with part of the construction broken away and in section;

Fig. 3 a partial section on the line 3—3 of Fig. 2;

Fig. 4 a partial section on the line 4—4 of Fig. 1; and,

Fig. 5 a partial section on the line 5—5 of Fig. 2.

My improved sled comprises a main body 55 portion or platform 6 which is oblong and approximately rectangular in form, and the

front end portion 7 of which is preferably of less transverse dimensions than the rear end portion 8. The body portion 6 is provided forwardly of the rear end portion 8 thereof with two feet receiving recesses or apertures 9 adapted to receive the feet of the operator, and these recesses or apertures are formed by depressing the body portion 6, as clearly shown in Fig. 4 of 65 the drawing, but it will be understood that said depressions may be formed in any desired manner.

Secured to the rear end portion 8 of the frame 6 are two runners 10 which are located at the opposite sides of said frame and are reinforced by V-shaped brace members 11 secured to the frame 6.

The front end portion 7 of the frame 6 is raised to a slight extent as shown at 12 and is provided with an upwardly directed 75 bearing 13 in which a shaft 14 is mounted. The lower end portion of the shaft 14 is secured to a supplemental frame member 15 rotatably mounted beneath the front portion 7 of the main frame 6 and spaced therefrom by an enlarged collar portion 16 on the shaft 14.

The supplemental frame member 15 is approximately rectangular in form and 85 secured to the bottom face thereof are two runners 17 reinforced by V-shaped brace members 18, which are also secured to said frame member.

Adjustably mounted on the upper end 90 portion of the shaft 14 is a handle member 19 provided at its upper end with a hand-piece 20 and at its lower end with a forked head 21, the side members 22 of which are provided with elongated apertures 23, in 95 which a pin 24, secured transversely of and to the shaft 14, operates. The forked head 21 is provided on opposite sides with downwardly directed extensions 25 which form a recess or aperture 26 in the head 21 in which 100 the upper end of the shaft 14 rests in the position of the handle member 19 shown in full lines in Figs. 1 and 2, and this construction serves to rigidly support the handle member in a vertical position. By 105 resting the handle member 19 on the shaft 14 so that the downwardly directed extensions 25 clear the upper end of said shaft said handle member may be swung forwardly or backwardly as may be desired, 110 and the forward movement thereof is indicated in dotted lines in Fig. 2 of the draw-

ing. In this position of the handle member the sled may be drawn by said handle member. A sleeve 27 is secured to the shaft 24 above the bearing 13 to prevent the shaft 5 14 from dropping through the main frame member 6 in carrying the sled from place to place.

In the use of my improved push sled, the operator places one foot within one of the 10 recesses or apertures 9 and one or both hands upon the handpiece 20 of the handle member and the other foot is used to push the sled over the ground until sufficient progress is made to enable the operator to place said 15 other foot within the other recess or aperture 9 and proceed to coast over the ground until the sled comes to a stop, after which the above operation may be repeated. By reason of the adjustability of the front or 20 steering runners 17 the push sled may be guided over the ground, turned around corners and the like by simply rotating the handle member 19 in the direction at which it is desired to turn.

25 It will also be apparent, however, that while I have described my invention as particularly designed for use as a push sled,

the same may be used in coasting down hills in which use the operator may sit or stand upon the main frame member 6, and while I have shown certain details of construction for carrying my invention into effect, it will be understood that I am not necessarily limited to these details, and various changes therein and modifications thereof may be 30 made, within the scope of the appended claims, without departing from the spirit of my invention or sacrificing its advantages.

Having fully described my invention, what I claim as new and desire to secure by 40 Letters Patent, is:—

A sled of the class described involving a main body or platform portion having countersunk feet receiving recesses or receptacles.

In testimony that I claim the foregoing as my invention I have signed my name in the presence of the subscribing witnesses this 45 24th day of August, 1920.

EDWARD J. GEBHARDT.
